(57) **CLAIM**

The ornamental design for an electric vehicle charger, as shown and described.

DESCRIPTION

FIG. 1 is a top front right side perspective view of an electric vehicle charger;

FIG. 2 is a top rear right side perspective view thereof;

FIG. 3 is a top rear left side perspective view thereof;

FIG. 4 is a top front left side perspective view thereof;

FIG. 5 is a top front perspective view thereof;

FIG. 6 is a bottom front right side perspective view thereof;

FIG. 7 is a bottom rear right side perspective view thereof;

FIG. 8 is a bottom rear left side perspective view thereof;

FIG. 9 is a bottom front left side perspective view thereof;

FIG. 10 is a bottom front perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof;

FIG. 16 is a bottom plan view thereof; and,

FIG. 17 is a top front right side perspective view thereof,

shown with additional broken line subject matter.

The broken lines in the drawings illustrate environmental structure and portions of the electric vehicle charger that form no part of the claimed ornamental design.
